EASEL

Louis Solem, Minneapolis, Minn.

Application March 1, 1946, Serial No. 651,290

5 Claims. (Cl. 120—28)

1

My invention relates broadly to easels and more specifically is in the nature of a general purpose prop or article-supporting bracket.

One of the objects of my invention is to provide a device of the general character above described which can be anchored to and supported by numerous objects such as typewriters, books, shelves or ledges of practically any type.

Another object of my invention is to provide such a structure which is inexpensive and easy to manufacture, and which is extremely durable.

A still further object of my invention is to provide devices of the kind described which can be used in cooperative arrangement whereby one of the devices can be used as a support or base for the other.

The above and still further objects of my invention will become apparent from the following detailed specification, appended claims, and attached drawings.

Referring to the drawings wherein like characters indicate like parts throughout the several views:

Fig. 1 is a front elevation illustrating my novel easel supporting a stenographer's book on the ledge of a typewriter, some parts being shown in dotted lines;

Fig. 2 is a side elevational view of Fig. 1, some parts being broken as shown in section;

Fig. 3 is a perspective view illustrating the use of my novel structure on the cover of a book;

Fig. 4 is a view corresponding somewhat to Fig. 3 showing a slightly different use of the easel; and

Fig. 5 is a perspective view illustrating the use of two of my novel devices in cooperative arrangement whereby to provide a base and supporting easel.

Referring more specifically to the drawings, the numeral 1 indicates a normally upstanding body portion of the easel upon which the article to be supported is generally adapted to rest. Body 1 is in the nature of an elongated bar. It is obvious that the width of the body portion may vary considerably depending upon the nature of the article sought to be supported thereby.

At the base of the body portion 1, it will be observed that the elongated bar is bent backwardly upon itself to form a clip 2, the axis of which is substantially parallel to the body por-

tion 1 and which is in close proximity to the body portion 1, especially at the top of the fold or as indicated at 3 (see Fig. 4). An integrally formed article-supporting shelf 4 extends forwardly from the base of clip 2, preferably, and as shown, at an acute angle to the bar or body portion 1. At its extreme outer edge, the shelf 4 is provided with a downturned portion 5 which terminates in a backwardly formed hook 6. Also preferably, and as shown, the extreme upper end of the bar-like body portion 1 is formed backwardly at an obtuse angle as illustrated by the numeral 7. One obvious purpose of this, particularly as shown in Fig. 2, is to facilitate the folding of the pages or the cover of a book or the like backwardly thereover.

Figs. 1, 2 and 4 illustrate the use of my novel device in use on a typewriter 8 having a conventional shelf-like cover 9 with a downturned lip or flange 10. In Figs. 1 and 2, one type of note book is illustrated wherein one of the reinforced covers 11 is shown as having its extreme outer end 11a forced between the lower end of body portion 1 and retaining clip 2 whereby the same is securely held in position. The other cover 12 is shown as being allowed to extend over the backwardly turned top portion 7. The arrangement shown in Fig. 4 is identical in all respects except that a different type of stenographic note book is illustrated. In both of these structures it will be observed that the pages of the book are allowed to come to rest upon the shelf 4.

In Fig. 3, the device is shown as being anchored to the reinforced cover 13 of a book 14. However, it should be understood that my easel can be used with or anchored to a shelf of any thickness and this may be accomplished by merely varying the length of the depending portion 5 to accommodate a given shelf.

Fig. 5 illustrates further, the importance of the backwardly bent or formed portion 7 which makes it possible to anchor the upright member to the cooperating substantially horizontal member which has been turned so that the normally back-turned end 7 points in downward direction.

While I have found it very advantageous to form my structure from a single piece of metal, in the form of a bar or the like, it should be understood that the same can be formed from plastic

or any other suitable material with equally good results, if desired.

Furthermore, it should be understood that in the use of this novel device, articles (depending entirely upon the nature) may be supported solely by inserting their extreme lower ends between the lower end of bar-like body portion 1 and retaining clip 2, by resting them solely upon the retaining shelf 4, by combining or utilizing both the shelf 4 and the retaining clip 2.

What I claim is:

1. An easel comprising an elongated supporting bar, a laterally offset integrally formed article retaining lip extending upwardly from the base of said bar, and in close proximity thereto, and an integrally formed article supporting shelf extending forwardly from said retaining lip, said shelf at its extreme outer edge being formed downwardly and backwardly to provide an anchoring hook.

2. The structure defined in claim 1 in which said supporting shelf extends forwardly from said retaining lip at an acute angle to said bar.

3. The structure defined in claim 1 in which the extreme upper end of said bar is backwardly turned at an obtuse angle.

5 4. In a device of the kind described, a metal bar 10 bent to form a normally upstanding body portion, a forwardly offset loop in close proximity to said body portion, an article supporting shelf which extends forwardly from said loop at an acute angle to said normally upright body portion, and an anchoring hook extending downwardly and backwardly from the extreme outer edge of said outer shelf.

15 5. The structure defined in claim 4 in which the extreme upper end of said normally upright body portion is bent backwardly at an obtuse angle.

LOUIS SOLEM.
